UNITED STATES PATENT OFFICE.

LESTER E. VAN HISE, OF ALTADENA, CALIFORNIA, ASSIGNOR TO JAMES V. BALDWIN,
OF LOS ANGELES, CALIFORNIA.

FUEL-FEED SYSTEM FOR INTERNAL-COMBUSTION ENGINES.

Application filed May 12, 1925. Serial No. 29,822.

My invention is designed for use in transferring fluid from one location to any other desired location. More particularly, it is designed for transferring fuel from a storage 5 tank on a motor vehicle to the carburetor of an internal combustion engine carried by the vehicle to move it.

The main object of my invention is to provide a simple and effective fuel feed device 10 which will be automatic in its operation and will require little or no attention to keep it operative.

Other objects of the invention will become apparent as the detailed description thereof 15 proceeds.

In the drawing:—

Figure 1 illustrates in elevation my invention as applied to the power unit of a motor vehicle; and

20 Figure 2 is a fragmentary cross sectional view of my improved fuel feeding apparatus. In the drawing, A designates a motor vehicle provided with an internal combustion engine 1 having the usual carburetor 2, storage tank 3, and exhaust manifold 4. The 25 means for transferring fuel from this tank 3 to the carburetor 2, includes a heat pump P comprising a tubular well 5 closed at one end thereof and having a screwthreaded stud 6 projecting from this end and having its 30 open end 7 screw threaded. This well or bottle 5 passes through an opening 8 in the exhaust manifold 4 and is secured therein by a nut 9 engaging the screwthreads of the 35 stud 6 which passes through a suitable aperture in the manifold 4. Between its ends, the bottle 5 is provided with an annular flange 10 which forms a closure seat for the bottle within the manifold 4 when the nut 9 40 is drawn up tight on the stud 6.

A T-head 11 has its middle branch 12 screwed onto the end 7 of the bottle 5, and has pipes 13 and 14 fixed to and extending from its other branches 15 and 16, respectively. The other end of pipe 13 is connected to one end of a check valve V on the end of a fuel conducting pipe 17 leading from the main supply tank 3. Pipe 14 has its other end connected to a similar valve V1 45 fixed to the head 18 of the auxiliary storage tank 19. This tank 19 is fixed in any convenient position on the vehicle to cause fuel to flow therefrom by gravity to the carburetor 50

2. As shown in the drawing, tank 19 is secured to the vehicle's dashboard D by 55 a band 20, and is connected by an overflow pipe 21 to the supply tank 3 and by a pipe 22 to the carburetor 2.

The check valves V and V1 are of the common spring controlled ball type, but may 60 be of any other suitable type and need be used only on the auxiliary tank side of the heat pump if desired. These valves act in the same direction; that is, they unseat to permit fuel to flow from the main tank to 65 the pump P and the tank 19 only, and seat to prevent the flow of fuel in the opposite direction.

Within the bottle member 5, a second tubular member 23, slightly less in external diameter than the internal diameter of bottle 5, is adjustably suspended concentrically within member 5 by a screw 24 engaging the closed end 25 of the member 23. The bottle 5 extends for about one-half of its length 70 outside of the exhaust duct 4 and the member 23 extends partly within and partly without this duct 4 with the space in bottle 5 above the end 25 forming an adjustable fuel cooling and condensing chamber. 75

The operation of the apparatus is somewhat as follows: Assuming that all the parts of the transferring apparatus are initially primed; when the engine is started, the heat from the exhaust gases passing through the 80 exhaust manifold 4 expands the liquid fuel in the bottle 5 and in the vapor trap 23 and vaporizes a part of this fuel. This expansion and vaporization causes part of the fuel in bottle 5 to be expelled therefrom and past 85 the valve V1 into the auxiliary tank 19, the valve V in the meantime preventing the flow of this expelled fuel back to the main supply tank 3. The inertia of the fuel expelled from the bottle 5 and the condensation of 90 the expelling vapor as it reaches the cooler parts of the pump P creates a vacuum behind the expelled column of fuel which reduces the pressure on valve V1, permitting it to be closed by its spring, and raises or opens 100 valve V to draw in a fresh cool supply of fuel to the pump P.

The fuel transferring action is continuous-pulsating providing the inner member 23 is properly adjusted within the bottle 5. As 105 fed to the auxiliary tank 19 by the pump

P, the fuel consists of alternate strata of liquid and vapor. It is to ensure proper proportioning of the vapor strata to the liquid strata that the inner vapor trap member 23 is made adjustable in the pump bottle 5. If the vapor strata were too large in volume, relative to the liquid strata, sufficient liquid fuel would not be transferred to the auxiliary tank 19, to keep the engine running, and the auxiliary tank would eventually be emptied and the engine stopped.

Particular attention is directed to the arrangement of the inner pump member 23 with its closed vapor trap end 25 directly in the path of the cool liquid fuel drawn from the main supply tank 3, which causes a rapid condensation of vapor remaining in the pump after expulsion of a strata of liquid therefrom with a consequent quick increase in vacuum to draw fuel from the main tank 3.

It will be apparent from the drawing that adjustment of the inner member 23 into or out of the exhaust duct 4 will cause variation in the quantities of fuel vaporized by the heat of the manifold gases, and that this adjustment will control the relative proportions of the expelled strata of liquid fuel and the fuel expelling strata of vapor.

Obviously, various changes and modifications may be made in the apparatus described herein without departing from the spirit of the invention and the scope of the appended claims.

Having thus disclosed my invention, what I claim as new and desire to secure by Letters Patent is:—

1. A thermal pump including a tubular receptacle having valved intake and discharge connections, a tubular shell open at one end and closed at its other and arranged in said receptacle to provide a relatively constricted passage between the shell and the receptacle and a sealed vapor chamber within the shell when the receptacle is supplied with liquid, and means for adjusting said shell in said receptacle.

2. A fuel pumping system for an internal combustion engine comprising in combination with the exhaust pipe of the engine, an open fuel supply tank, a thermally operated pump having a chamber disposed in part within said exhaust pipe, a feed pipe leading from the fuel supply tank to the pumping chamber, a check valve in said pipe, a discharge pipe also communicating with said chamber, a check valve in said discharge pipe, a reservoir for receiving liquid discharged by said discharge pipe, a feed connection from said reservoir to the carburetor of the engine, and an overflow pipe leading from the reservoir to the supply tank.

3. In a liquid-fuel pumping apparatus of the class described, the combination with a source of liquid-fuel supply and the exhaust

manifold of an engine, of a pumping bottle having its closed end disposed within said manifold, valved intake and discharge connections communicating with the upper end of the bottle, and a tubular shell closed at one end and open at the other and arranged within the bottle to provide a liquid sealed vapor chamber when the bottle is supplied with liquid-fuel.

4. In a liquid-fuel pumping apparatus of the class described, the combination with a source of liquid-fuel supply and the exhaust manifold of an engine, of a pumping bottle having its closed end disposed within said manifold, a cap fitted to the open end of said bottle, valved intake and discharge connections communicating with said cap, and a tubular shell closed at one end and open at the other and arranged within the bottle to provide a liquid sealed vapor chamber when the bottle is supplied with liquid-fuel.

5. In a liquid-fuel pumping apparatus of the class described the combination with a source of liquid-fuel supply and the exhaust manifold of an engine, of a pumping bottle having its closed end disposed within said manifold, a cap fitted to the open end of said bottle, valved intake and discharge connections communicating with said cap, and a tubular shell carried by said cap and suspended within the bottle to provide a relatively constricted space between the shell and the bottle and also provide a liquid sealed vapor chamber when the bottle is supplied with liquid fuel.

6. In a liquid fuel pumping apparatus of the class described, the combination with a source of liquid fuel supply and the exhaust manifold of an engine, of a pumping bottle having its closed end disposed within said manifold, a cap fitted to the open end of said bottle, valved intake and discharge connections communicating with said cap, and a tubular shell adjustably carried by said cap and suspended within the bottle to provide a relatively constricted space between the shell and the bottle and also provide a liquid sealed vapor chamber when the bottle is supplied with liquid-fuel.

7. A thermal pump of the class described including a tubular receptacle having valved intake and discharge connections, and a tubular shell open at one end and closed at the other and arranged within the tubular receptacle to provide a relatively constricted passage between the shell and the receptacle and also provide a liquid sealed vapor chamber within the shell when the receptacle is supplied with fluid.

8. In a fluid feeding device of the class described, the combination with a source of heat and a source of fluid supply, a pumping bottle having its closed end disposed within the zone of heat influence, valved intake and discharge connections communicating with

the open end of the bottle, and a tubular pumping shell arranged within the bottle and having a closed end and an open end, the said open end being disposed toward the bottom 5 of the bottle and being sealed by liquid within the bottom thereby cooperating with the said closed end to provide a sealed vapor

chamber adapted to discharge toward the bottom of the bottle when the effect of heat on the bottom of said bottle expands the 10 vapor in said vapor chamber.

In testimony whereof I have signed my name to this specification.

LESTER E. VAN HISE.
